EUGENE F. COOK, OF RICHMOND HEIGHTS, MISSOURI, ASSIGNOR TO LOUIS H. KUHLMANN AND ARTHUR H. KUHLMANN, COPARTNERS DOING BUSINESS AS KUHLMANN METAL WEATHER STRIP COMPANY, OF ST. LOUIS, MISSOURI

WEATHER STRIP

Application filed April 26, 1926. Serial No. 104,652.

My invention relates to metal weather strips and more particularly to spring strips having angularly disposed and hemmed edges.

5 These strips are usually made of spring bronze and provided with a nailing edge, for attachment to the door frame, and a free or spring edge, for pressure against the edge of the door when it is closed, these edges being angularly and oppositely disposed relative to the body of the strip. The contact between the strip and the door edge prevents drafts and air currents from entering the building provided there is a substantially uniform 10 pressure or tension exerted by the strip along the entire door edge.

In practice it has been difficult to obtain uniform contact on account of the irregularity of the door edge and the tendency of 20 the strip to buckle and bulge and lose its flexibility when it is nailed in place with its free edge spaced from the door frame. Furthermore, the flat spring material which is used for these strips is very susceptible to internal 25 strains and stresses which produce bulges, and, when both edges of the material are hemmed in the process of fabricating the strip, the bulges and buckles become so numerous that it is practically impossible to obtain 30 a strip which will accommodate itself to the contour of the door edge.

The object of my invention is to provide a double hemmed, angle-edged, spring, metal 35 weather strip having means for controlling and equally distributing the internal strains which are produced in hemming its edges so that the strip will be flexible, true and regular throughout its length when put to use.

40 Another object of my invention is to provide a spring metal weather strip having hemmed edges disposed at an angle to the body of the strip and which, when fastened in position, will have a free edge adapted to 45 make contact uniformly along the entire door edge.

A further object of my invention is to provide a hemmed spring metal weather strip adapted to be formed in a coil and which 50 when unwound from the coil will present

straight edges and a surface which is regular and free from bulges or buckles.

A still further object of my invention is to provide a hemmed, angle-edged, coilable 55 spring metal weather strip in which the strains produced in hemming and coiling are distributed along predetermined paths or lines throughout the length of the strip.

My invention consists in the novel construction, combination and arrangement of parts 60 as hereinafter fully, clearly and concisely described, definitely pointed out in my claim and illustrated by the accompanying drawing, in which:

The figure is a perspective view of a coil of 65 my weather stripping.

Referring to the drawing, 1 is the nailing edge of my strip, and 2 is the free or spring edge, the nailing edge preferably being somewhat greater in width than the free edge for 70 facility in attaching the strip to a door frame; each of these edges is turned on itself to provide a roll or hem, 3, in order to stiffen the edge and prevent its vibration by air currents. As shown in the drawing, these edges 75 are then bent at an angle to the body of the strip, the angle being such that when the edge 1 is attached to a door frame, the body of the strip will be inclined relative to the face of the door frame and edge 2 will be 80 spaced therefrom. Intermediate these edges is the body of the strip which comprises a series of inclined surfaces 4, forming ridges 5, and grooves 6, having a longitudinal trend 85 throughout the length of the strip. By preference, these ridges and grooves are parallel and equally spaced and the inclined surfaces are of equal width and like trend.

It is obvious that the body of the strip, in practice, is not of uniform cross-section 90 and that in forming the hem, 3, strains will occur which result in bulges in the body, and that an alteration of these strains will occur and further bulges be produced when the edges 1 and 2 are bent at opposite angles relative to the body. It is likewise obvious that some of these bulges will be upward and others downward and that if they are not restrained and limited in their formation, the fastening of the edge 1 to the door frame will 95 100

so distort the edge 2 and the body of the strip that no uniform contact can be had or maintained between the strip and the door edge.

18 I have found that these bulges can be absorbed or controlled by forming the ridges 5 and grooves 6 in the body and that by this means the bulges are distributed along definite regular lines and their character is 10 changed from irregular depressions and distortions, at sporadic intervals, into a series of predetermined upwardly and downwardly inclined surfaces which are not only harmless to the strip but give it smoothness, pliability 15 and flexibility for coiling and nailing, resistance against buckling and a tendency to lay flat when uncoiled.

I claim:—

20 A metal weather strip adapted to be coiled into roll form and consisting of a single piece of material including a nailing edge of double thickness, the thicknesses thereof being compressed into adjacency to form a stiffening portion; a central or body portion of the 25 strip having a trend at a distinct angle to the nailing edge, said central portion consisting, on each face, of alternate ridges and furrows, the furrowed portions being of relatively flattened, V shape and of distinctly 30 angulate conformity, the ridges on one face of the strip being coincident with the furrowed portions of the opposite face of the strip and the ridged and furrowed portions being of substantially uniform width and 35 spacing across the strip; the opposite edge of the strip terminating in a portion of double thickness, the thicknesses lying in close adjacency and constituting a free or pressure edge, disposed at an angle to the trend of the central or body portion, and of slightly 40 less width than that of the nailing edge of the strip, said edges each being joined to the central body portion at an angle corresponding substantially with that formed between adjacent furrows and ridges of the body portion, 45 whereby the strip presents a substantially regular, transverse zig-zag or saw-tooth section, characterized by the absence of grooves or corrugations of rounded contour.

50 EUGENE F. COOK.
